Inventor:

Géza Bokor.

By Major B. St. John,
Attorneys.

UNITED STATES PATENT OFFICE.

GÉZA BOKOR, OF MELROSE PARK, ILLINOIS.

NUTCRACKER.

Application filed November 30, 1921. Serial No. 518,956.

To all whom it may concern:

Be it known that I, GÉZA BOKOR, a subject of Hungary, residing at Melrose Park, in the county of Cook and State of Illinois, have invented new and useful Improvements in Nutcrackers, of which the following is a specification.

This invention relates to devices for breaking the shell of nuts, and its object is to provide a device of this kind embodying certain novel and improved structural details, and modes of operation to be described in detail hereinafter, the device being designed more particularly for facile operation and for preventing crushing of the meat of the nuts.

The object stated is attained by means of a combination and arrangement of parts to be hereinafter described and claimed, and in order that the same may be better understood, reference is had to the accompanying drawing, forming a part of this specification.

In the drawing, Figure 1 is an elevation of the device; Fig. 2 is a similar view, partly in section, illustrating the operation of the device, and Figs. 3 and 4 are cross sections on the lines 3—3 and 4—4 respectively of Fig. 2.

Referring specifically to the drawing, 5 and 6 denote two pivotally connected levers, the connection being made at one end by a suitable pivot pin 7, and the other ends of the levers being shaped to form hand-grips. The device is of such size that it may be conveniently grasped and operated by one hand. The levers are held normally spread by a spring 8 coiled around the pivot 7 and having its free ends pressing against the inside of the levers.

Adjacent to the pivot 7, the lever 5 has a recess 9 opening through its inner edge, in which recess 9 are pivotally mounted two jaw members 10 and 11 which protrude sufficiently from said edge to engage the nut to be cracked. The protruding edge portions of the jaw members have concavely curved and serrated portions to obtain a firm grip on the nut, and the opposite or inner edge of the lever 6 has similarly curved jaw faces 12 for engaging the nut. The jaw 10 is nearer the pivot 7 than the jaw 11, and it is designed for operating on small nuts, whereas the jaw 11 is designed for operating on large nuts. The jaw faces 12 are properly located with respect to the

nut-engaging surfaces of the jaw members 10 and 11 to cooperate with the latter for gripping the nuts.

The levers 5 and 6 are made of channelled stock, the channels facing each other, and the jaw members 10 and 11 seating in the recess or channel 9 of the lever 5. The jaw faces 12 are on a channel shaped insert 12^a seating in the channel of the lever 6, and secured therein by rivets or other suitable fasteners 12^b.

In the face of the jaw member 11 is a recess 11^a and opposite the same, the jaw face 12 has a recess 11^b. The purpose of these recesses is to facilitate the breaking of the shells of the pecan nuts, the ends of the same being seated in the recesses, so that the pressure is applied against the ends of the nuts, whereby they are made to crack more readily.

The adjacent ends of the jaw members 10 and 11 are connected so that they may rock together, a pin-and-slot connection 13 being provided for this purpose. The pivotal connection of the jaw member 10 with the lever 5 is shown at 14, and that of the jaw member 11 at 15, these connections being at the ends of the jaw members remote from their pivotally connected adjacent ends. It will therefore be seen that when either jaw member is forced inwardly, the other member partakes of the same movement. A spring 16 in the recess 9 bears against the pin 13 in such a way that the jaw members normally protrude from the inner edge of the lever 5.

The levers 5 and 6 are connected by a curved rack bar 17 having its teeth on its concave side which faces the pivotal connection 7. One end of the rack bar 17 extends loosely through the channel 9 and a guide aperture 9^a in the rear wall thereof rearwardly of the jaw member 11, and on the rear edge of said jaw member are teeth 18 which are adapted to become interlocked with the teeth of the rack bar when said jaw member is rocked as hereinbefore described by pressure of the nut thereagainst or against the jaw member 10. The other end of the rack bar passes loosely into the channel 19 of the lever 6. A cross pin 20 carried by lever 6 and extending through a longitudinal slot 21 in the rack bar provides a loose connection between the rack bar and the lever, and permits a limited sliding movement of the former relative to the latter. The end of the rack bar which passes

through and protrudes from the lever 5 has a side pin or other abutment 22 to prevent withdrawal of this end of the rack bar from said lever.

5 The back of the lever 6 carries a bridge piece 23 through which is threaded a screw 24 having its inner end opposite the end of the rack bar 17 which works in the channel 19, and between said end of the rack bar and 10 the bridge piece is located a coiled spring 25 which opposes the movement of the rack bar in the direction of the screw.

In operation, the nut to be cracked is placed between the jaw member 10 or 11 and 15 the opposite seat 12, according to the size of the nut, the levers 5 and 6 being swung toward each other to cause the nut to be gripped. Upon continuing to press the levers together, the jaw 10 is first rocked 20 backwards, which movement is communicated to jaw member 11, whereupon the teeth 18 of the latter become interlocked with the teeth of the rack bar 17. The rack bar is now locked to the lever 5, and upon 25 continuing to press said lever and the lever 6 together, the rack bar slides in the channel 19 until it is stopped by striking the screw 24 as shown in Fig. 2. The length of the stroke of the rack bar governs the extent of the travel of the levers 5 and 30 6 toward each other, and consequently the extent of the crushing action. The screw 24 can be advanced or retracted to shorten or 35 lengthen the stroke according to the character of the nut or the thickness of its shell, it being understood that the screw is to be adjusted to obtain a stroke just sufficient to crack the shell of the nut without crushing or bruising the meat. For nuts having a 40 thin shell, a very short stroke is sufficient to crack the same, whereas nuts having a thick shell require a longer stroke. The stroke is readily regulated by adjustment of the screw 24. The action hereinbefore described 45 also takes place if the nut is placed between the jaw member 11 and the opposite jaw face 12 of the lever 6, the initial action being the rocking of said jaw member to interlock its teeth 18 with the teeth of the rack 50 bar 17.

Upon releasing the grip on the levers 5 and 6 they spread to release the nut, this action being effected by the spring 8 which was compressed when the levers were drawn 55 together. When the pressure of the nut against the jaw members 10 or 11 is released, said members are restored by the spring 16 to their normal position, and upon moving to this position, the teeth 18 of jaw member 60 11 are disengaged from the teeth of the rack bar 17 so that the rack bar is now uncoupled from the lever 5.

I claim:

1. A nut cracker comprising a pair of pivoted levers, one of said levers having a jaw

face, a movable jaw member carried by the other lever opposite the jaw face, means associated with the levers for gaging the extent of the closing movement thereof, said means being normally inoperative, and 70 means operable by the movement of the jaw member to place the aforesaid gaging means in operative position.

2. A nut cracker comprising a pair of pivoted levers, one of said levers having a 75 pair of jaw faces, a pair of movable jaw members carried by the other lever opposite the jaw faces, and connected to move together, means associated with the levers for gaging the extent of the closing movement 80 thereof, said means being normally inoperative, and means operable by the movement of either of the aforesaid jaw members to place the aforesaid gaging means in operative position.

3. A nut cracker comprising a pair of pivoted levers, one of said levers having a jaw face, a movable jaw member carried by the other lever opposite the jaw face, a bar spanning the levers and having a slidable connection therewith, means operable by the movement of the jaw member for coupling the bar to the lever carrying said jaw member, and a stop carried by the other lever for limiting the sliding movement of the bar 95 relative to said lever when coupled as aforementioned.

4. A nut cracker comprising a pair of pivoted levers, one of said levers having a jaw face, a movable jaw member carried by the 100 other lever opposite the jaw face, a rack bar spanning the levers and having a slidable connection therewith, means operable by the movement of the jaw member for coupling the rack bar to the lever carrying said jaw 105 member, said means being teeth on the jaw member which interlock with the teeth of the rack bar when the jaw member is moved, and a stop carried by the other lever for limiting the sliding movement of the rack 110 bar relative to said lever when coupled as aforementioned.

5. A nut cracker comprising a pair of pivoted levers, one of said levers having a jaw face, a movable jaw member carried by the 115 other lever opposite the jaw face, a bar spanning the levers and having a slidable connection therewith, means operable by the movement of the jaw member for coupling the bar to the lever carrying said jaw member, and an adjustable stop carried by the other lever for limiting the sliding movement of the bar relative to said lever when coupled as aforementioned.

6. A nut cracker comprising a pair of pivoted levers, one of said levers having a jaw face, a movable jaw member carried by the other lever opposite the jaw face, a rack bar spanning the levers and having a slidable connection therewith, means operable by the 125 130

movement of the jaw member for coupling the rack bar to the lever carrying said jaw member, said means being teeth on the jaw member which interlock with the teeth of the rack bar when the jaw member is moved, the other lever having a recess into which the rack bar slidably extends, a cross-piece spanning the recess, and a screw carried by the cross-piece opposite the end of the rack bar for limiting its sliding movement relative to the last-mentioned lever when coupled as aforesaid.

7. A nut cracker comprising a pair of pivoted levers, one of said levers having a jaw face, a movable jaw member carried by the other lever opposite the jaw face, a rack bar spanning the levers and having a slidable connection therewith, means operable by the

movement of the jaw member for coupling the rack bar to the lever carrying said jaw member, said means being teeth on the jaw member which interlock with the teeth of the rack bar when the jaw member is moved, the other lever having a recess into which the rack bar slidably extends, a cross-piece spanning the recess, a screw carried by the cross-piece opposite the end of the rack bar for limiting its sliding movement relative to the last-mentioned lever when coupled as aforesaid, and a spring interposed between the cross-piece and the adjacent end of the rack bar.

In testimony whereof I affix my signature.

GÉZA BOKOR.
